CLAIM

The ornamental design for a computer with pitched front bezel as shown and described.

DESCRIPTION

FIG. 1 is a front, right, top perspective view of the claimed design;

FIG. 2 is a front, left, top perspective view thereof;

FIG. 3 is a front, right, bottom perspective view thereof;

FIG. 4 is a front elevational view thereof;

FIG. 5 is a rear elevational view thereof; and,

FIG. 6 is a bottom plan view thereof.

The broken lines, shown in the drawings, represent portions of the Computer with Pitched Front Bezel and form no part of the claimed design.

1 Claim, 5 Drawing Sheets
